CLAIM

The ornamental design for a hair waving apparatus, as shown and described.

DESCRIPTION

FIG. 1 is a perspective view of the hair waving apparatus in accordance with the principles of the present disclosure; FIG. 2 is a left side elevation view of the hair waving apparatus;

FIG. 3 is a right side elevation view of the hair waving apparatus;

FIG. 4 is a top plan view of the hair waving apparatus; FIG. 5 is a bottom plan view of the hair waving apparatus; FIG. 6 is a front elevation view of the hair waving apparatus; FIG. 7 is a rear elevation view of the hair waving apparatus; FIG. 8 is a perspective view of an alternate embodiment of the hair waving apparatus;

FIG. 9 is a left side elevation view of the embodiment of the hair waving apparatus of FIG. 8;

FIG. 10 is a right side elevation view of the embodiment of the hair waving apparatus of FIG. 8;

FIG. 11 is a top plan view of the embodiment of the hair waving apparatus of FIG. 8;

FIG. 12 is a bottom plan view of the embodiment of the hair waving apparatus of FIG. 8;

FIG. 13 is a front elevation view of the embodiment of the hair waving apparatus of FIG. 8; and,

FIG. 14 is a rear elevation view of the embodiment of the hair waving apparatus of FIG. 8.

The broken lines shown in the drawings illustrate portions of the hair waving apparatus and form no part of the claimed design.

1 Claim, 8 Drawing Sheets
